Primary Examiner — Cynthia R Underwood

(74) Attorney, Agent, or Firm — Cramer Patent & Design PLLC; Aaron R. Cramer

(57) **CLAIM**

The ornamental design for a weight for submerged tubing, as shown and described.

DESCRIPTION

FIG. 1 is a perspective top front left view of a weight for submerged tubing, showing my new design;

FIG. 2 is a front elevation view thereof, wherein the rear elevation view is an identical image thereof;

FIG. 3 is a left elevation view thereof, wherein the right elevation view is an identical view thereof;

FIG. 4 is a top plan view thereof; and,

FIG. 5 is a bottom plan view thereof.

1 Claim, 5 Drawing Sheets(56)
